UNITED STATES PATENT OFFICE

2,209,840

APPARATUS FOR GROUP PACKAGE FORMING

Joseph P. McHugh, Scranton, Pa., assignor, by
mesne assignments, to Industrial Machine Cor-
poration, a corporation of Delaware

Original application June 6, 1933, Serial No.
674,568. Divided and this application June 1,
1936, Serial No. 82,961

12 Claims. (Cl. 242—43.3)

This application is a division of my copending application Serial No. 674,568, filed June 6, 1933, Patent No. 2,044,621, issued June 16, 1936.

This invention relates to a method and apparatus for group package forming of yarn through the medium of which the yarn, irrespective of size, may be packaged ready to be directly received in fabric forming machinery.

This invention has especial utility of multiple down-spinning processes and apparatus for throwing lustrous yarn. However, it is not limited in its field of utility to such use.

For purposes of illustration, the invention is herein shown and described as an improvement in a multiple down-spinning process and apparatus of the character in which the lustrous yarn is fully thrown and formed into the final package ready, without re-drawing, coning, or copping, to enter the fabric forming machinery in one continuous uninterrupted operation employing a single spinning step.

By employing the improvement of the present invention, both the silk throwing and cop or quill forming may be directly accomplished in one uninterrupted operation in a single machine.

It is also an object of the invention to provide a method and apparatus for forming quills or cops whereby the successive strand layers on the cops formed are effectively interlocked in a manner permitting unwinding in the shuttle on weaving without snarling.

A further object of the invention is to provide an improved method and apparatus for forming quills or cops by starting the winding at either end of the quill or cop to be formed and feeding the thread or strand with a traverse which is always less than the desired length of the quill or cop and with a relatively small gain until the other end of the quill or cop to be formed is reached, and then rapidly returning the thread or strand to the first end of the quill or cop and repeating the cycle until the cop is completely formed.

Other and more detailed objects and advantages will become apparent as the description proceeds.

The invention will be described by reference to the accompanying drawings wherein:

Figure 1 is a view in side elevation of a complete quill or cop forming machine unit;

Figure 2 is a front elevation of the machine shown in Figure 1;

Figure 3 is a detailed view showing a part of the traverse drive mechanism;

Figure 4 is a view taken at a right angle to Figure 3 showing the traverse control cams; and

Figure 5 is a detailed view showing the quill mounting and drive.

Referring to Figure 1, there is a base frame on which the entire mechanism is assembled.

A motor 2 is centrally carried on the frame 1 and drives a power belt 3. The frame 1 is designed to carry rows of complementary units at each side thereof. These are, however, constructed in duplication. Therefore, only a single left-hand unit is shown and will be described. The belt 3 drives pulleys 4 and 4'. The shaft 5 extends down from pulley 4' and carries a worm 6 at the lower end thereof which meshes with a worm gear 7 mounted on a shaft 8 carrying a sprocket 9. A sprocket chain 10 is trained around the drive sprocket 9. The sprocket chain 10 drives the traverse mechanism, designated broadly A, and also the roller mechanism designated broadly B. Chain 10 passes about sprockets 11, 12, and 13. Sprocket 11 in turn drives bevel gears 14 and 15, transmitting power to the shaft 16 suitably carried by the frame 1. Power is transmitted through shaft 16 for controlling the movement of the traverse mechanism A, to be later described in detail.

The sprocket 12 drives bevel gears 17 and 18 transmitting power to shaft 19 for driving the roller mechanism B. The quill spindle 20 carries an enlarged hub 21 normally in driving contact with the belt 3. The spindle 20 is so mounted at its base that it can be swung to and from contact with the drive belt 3 so that the spindle of any unit may be removed from driving engagement with the belt without stopping the machine or disturbing other units.

Coming now to a description of the mountings for the swifts or reels for the skeins, there is rigidly secured to the upper end of the frame 1 a main supporting arm 22. The arm 22 carries at its free end a central hub 23. The hub 23 in turn carries four arms 24, each carrying at its free end a swift or reel 25. Each reel 25 is constructed to receive a skein. The central hub 23 is rotatably carried by the arm 22 so that any swift or reel 25 may be brought within reach of the operator for tying broken strands or replacing skeins. A locking mechanism for holding the hub 23 in any given position of adjustment with respect to the arm 22 is provided and includes the latch detent 26 extending through arm 22 and adapted to engage the hub 23.

The manner of taking off the strands from the individual skeins is such that the hub 23 can be moved to and held in any position of adjustment without interfering with the operation of the machine. The end of the strand from each skein is threaded through a porcelain eye 28 carried by hub 23, and each strand then passes transversely of the hub 23 to the single porcelain condensing guide 29 carried by the arm 22' of the next adjacent unit. From the guide 29 the condensed strand, designated 30, is passed down to the roller mechanism B (see Figure 2).

Coming now to the roller mechanism B, a main

supporting bracket arm 31 is secured to the upper end of the base frame 1 and supports the entire roller mechanism. The shaft 19 passes longitudinally of the arm 31 to drive the roller 5 32 through suitable bevel gears.

A stop motion is provided, and the arrangement is such that, when the electromagnet 33 is energized through the closing of a circuit due to the breaking of a strand, the armature is attracted and causes disengagement of the roller driving gears, allowing the roller 32 to stop.

Passing now to the means for disconnecting the package or quill carrying spindle 20 from the driving belt 3, it will be noted that a latch bar 34 10 is provided at its outer end with an aperture through which extends a spindle releasing rod 35. The rod 35 is pivotally mounted at its lower end on a pivot 36, about which it is moved by the latch arm 34 when released by energization of 15 magnet 33.

As shown in Figure 2, the spindle releasing rod 35 extends behind a finger 37 carried by the mounting 38 for spindle 20. It will be observed that the mounting 38 is journaled upon a vertical 20 pivot 39 which is eccentric to the axis of spindle 20, the vertical pivot 39 being supported by a fixed bracket 40 carried by the frame 1. There is also carried by the bracket 40 a fixed brake shoe 41.

The action is as follows: The mounting 38 25 carrying the spindle 20 is normally urged toward the belt 3 by a coil spring to insure driving engagement between belt 3 and spindle hub 21. Now, when magnet 33 causes the release of latch bar 34, the latter, due to the action of a spring, 30 forces spindle releasing rod 35 outwardly against the finger 37 to swing the spindle mounting 38 about the eccentric pivot 39 and move the spindle hub 21 from engagement with belt 3 and into engagement with fixed brake shoe 41 to stop the 35 spindle.

Before leaving the spindle releasing rod 35, it will be further observed that when this rod is moved to release spindle hub 21 from driving engagement with belt 3, it also opens, through the 40 medium of rod 42, contacts 43 in series with magnet 33 to de-energize the same. The spindle releasing rod 35 remains in its released position, until manually restored by re-engagement of a 45 latch on bar 34, to maintain the roller 32 and the spindle 20 inoperative.

Returning to the roller 32, the composite strand 30 coming from the porcelain guide eye 29 is drawn through a porcelain eye 44 supported by the latch bar 34 in a position directly above the 50 left-hand end of roller 32, as viewed from the front. A porcelain guide 45 is mounted immediately above the roller 32. The roller 32 is provided on its circumference with three flat-bottomed grooves or channels separated by square 55 shouldered flanges.

The thread 30 leaves the eye 44, enters the 60 groove adjacent the left side of roller 32, is carried once around roller 32 in this groove, thence passes over porcelain guide 45 into the next groove and once again around the roller 32, thence passing again over porcelain guide 45 to the next 65 groove and thence through eye 46 and on to the traverse mechanism hereinafter described. The 70 thread is caused to roll axially of the roller 32 in the grooves thereon, whereby the yarn delivered to the traverse mechanism is partially twisted. The flat-bottomed grooves together with the 75 square shouldered flanges therebetween are particularly advantageous in giving a tightly twisted

yarn and preventing snarling and entangling of the yarn upon the roller.

The improved traverse operating and control mechanism by which the novel method of package forming is accomplished will now be described. Returning to the driven shaft 16, a heart-shaped cam 47 is carried thereby, which oscillates an arm 48 loosely journaled upon a rocker shaft 49 extending parallel to shaft 16.

The arm 48 carries a cam follower roller 50 which rides on cam 47 to cause oscillation of arm 48. The arm 48 also carries a shaft 51 journaled therein, on one end of which is fixed a half-heart cam 52 and on the other end of which is carried a worm gear 53. The worm gear 53 and half-heart cam 52 are driven from shaft 16 by means of sprocket 54 on shaft 16, chain 55, and the sprocket 56 mounted on rotating sleeve 57 loosely journaled upon shaft 49. The sleeve 57 carries at its opposite end a worm gear 58 which drives a worm gear 59 upon a shaft 60 extending at right angles to shaft 49 and journaled in a bearing 61 carried by rocker arm 48. The shaft 60 carries at its opposite end a worm 62 which drives gear 53 and half-heart cam 52.

The shaft 49 has affixed thereto a rocker arm 63 which carries at its free end a cam follower roller 64 riding upon the half-heart cam 52. Shaft 49 carries at its outer end a bell-crank lever 65 (see Figure 2), the horizontal arm of which carries a roller 102 at its free end. The roller 102 engages a thrust plate 67 on the lower end of the traverse reciprocating rod 68 mounted in a guide bearing 69, supported on frame 1 and carrying horizontal ring supporting rods 70 at its upper end. The rods 70 are common to a plurality of units and carry the ring 71. The vertical arm of bell-crank 65 is pivotally connected to a rod 72 which operates bell-cranks similar to 65, which cooperate to actuate ring-supporting rods 70. The ring 71 is provided with a suitable traveler that receives and guides the thread 30 as it is spun and wound to form a cop or quill on the spindle 20.

The operation of the traverse is as follows: 45 The heart cam 47 directly driven by shaft 16 rotates at a relatively rapid speed and produces, through arms 48, 63, and 65, traverse movement of uniform amplitude. The amplitude of the uniform traverse is controlled by the size of cam 50 47 and is intentionally always less than the desired length of quill or cop to be formed. The half-heart cam 52 controls the traverse gain on the quill. Cam 52 moves much slower than cam 47. A ratio of 15 to 1 is found satisfactory, although this may be varied if desired. On each rotation of cam 47 there is but a small movement of cam 52 which, translated to the traverse, causes it to gain on each rotation of cam 47 proportioned to the movement and pitch of the 60 cam 52.

The cam 52 is so constructed that the cam follower 64 rides, during seven-eighths of each revolution thereof, on the curved face of the cam and returns to the point of beginning in but one-eighth of a revolution of cam 52. It will thus be observed that after the total gain provided by the curved surface of cam 52 has been effected, there is a quick return to the point of beginning. Due to the form of cam follower 64, the return 70 is effected in much less than one-eighth of a revolution of cam 52. Translated to the quill or cop the winding commences, for example, at the bottom, the upward traverse is uniform. The downward traverse is also uniform but is always 75

shorter than the upward traverse. When the top-most traverse is reached, the ring is rapidly returned to the bottom of the quill and the cycle repeated. The winding may be commenced at the top of the cone or quill and the action reversed by merely reversing the half-heart cam 52.

The cop or quill is built up from the bottom by successive layers of thread, each layer comprising a plurality of overlapping traverses. This results in the formation of a cop or quill having a very effective interlocking wind and one which will unwind in the shuttle on weaving without snarling.

No electrical diagram of the circuit for the electromagnet 33 of the stop mechanism is shown, it being obvious that this circuit is closed upon the breaking of any one of the strands coming from the skeins on reels 25 through the action of the rod carrying the porcelain eye 28 and that the circuit is broken by the spindle release rod when the stop mechanism has been actuated.

In accordance with the present invention, it is possible to throw silk and form crepe silk or rayon cops or quills in one uninterrupted operation with but one twisting and winding operation. This has never, to my knowledge, been heretofore accomplished. Crepe silk or rayon requires around sixty-five twists per linear inch, and no machine has heretofore been devised for both throwing the silk and giving a cop or quill of thread of this character directly ready for the shuttle of the loom. According to this invention, the quill spindle is driven at a very high speed approximating 15,000 R. P. M. With this permissible speed and the method of twisting and cop forming employed, I am able to turn out crepe silk or rayon quills or cops in one operation, taking the rovings from the skeins and producing finished headless packages ready, without re-drawing, coning, or copping, to directly enter fabric forming machinery.

While the invention has been herein illustrated and described as incorporated in a multiple ring spinning process and apparatus, it is to be understood that the group package forming features of the invention may be employed wherever found desirable and need not be associated with ring spinning. The group packaging of yarn employing the traverse mechanism of the present invention is exceedingly practicable in packaging yarns of various sizes. When employing the present invention, it is not necessary to change the builder ratio or rate of movement of the traverse with changes in yarn size. In group package forming as presently practiced, it is necessary to change the ratio of the builder motion depending upon the size of the yarn being packaged. This is entirely obviated by the present group package forming process and apparatus which is applicable to any yarn size.

The foregoing description is illustrative only, the invention being limited and restricted only by the scope of the appended claims.

Having thus described my invention, what I claim is:

1. Traverse mechanism for group package forming apparatus comprising thread guiding means, a rock shaft connected to said means to reciprocate the latter to effect winding of a package, a drive shaft parallel to the rock shaft, a first arm fast on the rock shaft, a second arm loosely mounted on the rock shaft, means connecting the drive shaft to the second arm for effecting oscillations of said arm of uniform amplitude, and means connecting the second arm

to the first arm for transmitting the oscillations of the second arm to the first arm and for causing a slow, gradual shifting of the first arm relative to the second arm in one direction of oscillation and a rapid shifting of the first arm relative to the second arm in the opposite direction of oscillation.

2. Traverse mechanism for group package forming apparatus comprising thread guiding means, a rock shaft connected to said means to reciprocate the latter to effect winding of a package, a drive shaft parallel to the rock shaft, a first arm fast on the rock shaft, a second arm loosely mounted on the rock shaft, means including a heart cam for connecting the drive shaft to the second arm for effecting oscillation of said arm of uniform amplitude, and means including a half heart cam for connecting the second arm to the first arm for transmitting the oscillations of the second arm to the first arm and for causing a slow, gradual shifting of the first arm relative to the second arm in one direction of oscillation and a rapid shifting of the first arm relative to the second arm in the opposite direction of oscillation.

3. Traverse mechanism for group package forming apparatus comprising thread guiding means, a rock shaft connected to said means to reciprocate the latter to effect winding of a package, a drive shaft parallel to the rock shaft, a first arm fast on the rock shaft, a second arm loosely mounted on the rock shaft, means including a heart cam carried and driven by the drive shaft for causing rotation of the drive shaft in one direction to effect oscillation of the second arm of uniform amplitude, and means including a half heart cam carried by the second arm for transmitting the oscillations of the second arm to the first arm and for causing a slow, gradual shifting of the first arm relative to the second arm in one direction of oscillation and a rapid shifting of the first arm relative to the second arm in the opposite direction of oscillation.

4. Traverse mechanism for group package forming apparatus comprising thread guiding means, a rock shaft connected to said means to reciprocate the latter to effect winding of a package, a drive shaft parallel to the rock shaft, a first arm fast on the rock shaft, a second arm loosely mounted on the rock shaft, means including a heart cam carried and driven by the drive shaft for causing rotation of the drive shaft in one direction to effect oscillation of the second arm of uniform amplitude, and means including a half heart cam carried by the second arm and driven from the drive shaft for transmitting the oscillations of the second arm to the first arm and for causing a slow, gradual shifting of the first arm relative to the second arm in one direction of oscillation and a rapid shifting of the first arm relative to the second arm in the opposite direction of oscillation.

5. Traverse mechanism for group package forming apparatus comprising thread guiding means, a rock shaft connected to said means to reciprocate the latter to effect winding of a package, a drive shaft parallel to the rock shaft, a first arm fast on the rock shaft, a second arm loosely mounted on the rock shaft, means including a heart cam carried and driven by the drive shaft for causing rotation of the drive shaft in a single direction to effect oscillations of the second arm of uniform amplitude, and means including a half heart cam carried by the second arm and constantly driven from the drive shaft

for transmitting the oscillations of the second arm to the first arm and for causing a slow, gradual shifting of the first arm relative to the second arm in one direction of oscillation and a rapid shifting of the first arm relative to the second arm in the opposite direction of oscillation.

6. Traverse mechanism for group package forming apparatus comprising thread guiding means, a rock shaft connected to said means to reciprocate the latter to effect winding of a package, a drive shaft parallel to the rock shaft, a first arm fast on the rock shaft, a second arm loosely mounted on the rock shaft, means driven by the drive shaft for effecting oscillations of the second arm of uniform amplitude, means carried by the second arm for transmitting the oscillations of the second arm to the first arm, and means for constantly moving the means carried by the second arm for causing a slow, gradual shifting of the first arm relative to the second arm in one direction of oscillation and a rapid shifting of the first arm relative to the second arm in the opposite direction of oscillation.

7. Traverse mechanism for group package forming apparatus comprising thread guiding means, a rock shaft connected to said means to reciprocate the latter to effect winding of a package, a drive shaft parallel to the rock shaft, a first arm fast on the rock shaft, a second arm loosely mounted on the rock shaft, a heart cam driven by the drive shaft for effecting oscillations of the second arm of uniform amplitude, a half heart cam carried by the second arm for transmitting the oscillations of the second arm to the first arm, and means for constantly moving the half heart cam carried by the second arm for causing a slow, gradual shifting of the first arm relative to the second arm in one direction of oscillation and a rapid shifting of the first arm relative to the second arm in the opposite direction of oscillation.

8. Traverse mechanism for group package forming apparatus comprising thread guiding means, a rock shaft connected to said means to reciprocate the latter to effect winding of a package, a drive shaft parallel to the rock shaft, a first arm fast on the rock shaft, a second arm loosely mounted on the rock shaft, means driven by the drive shaft for effecting oscillations of the second arm of uniform amplitude, means carried by the second arm for transmitting the oscillations of the second arm to the first arm, a shaft journaled in the second arm and drivingly connected to the means carried by the second arm, and a train of gearing between the drive shaft and the shaft journaled on the second arm for effecting movement of the means carried by the second arm to cause a slow, gradual shifting of the first arm relative to the second arm in one direction of oscillation and a rapid shifting of the first arm relative to the second arm in the opposite direction of oscillation.

9. A group package forming apparatus comprising supporting means for a plurality of package supports, means for rotating said package supports, thread guiding means for each package support, means for connecting said thread guiding means for simultaneous traverse movement, a bell crank lever operatively connected to said connecting means, a rock shaft supporting and driving said bell crank lever, a drive shaft parallel to the rock shaft, a first arm fas-

tened on the rock shaft, a second arm loosely mounted on the rock shaft, a heart cam keyed to the drive shaft for effecting oscillations of the second arm of uniform amplitude, a rotatable shaft carried by the second arm, a half heart cam mounted on said rotatable shaft and engaging the first arm for transmitting the oscillations of the second arm to the first arm, and a train of mechanical elements carried by and associated with the drive shaft, the rock shaft and the second arm for constantly rotating the shaft carried by the second arm from the drive shaft to cause the half heart cam to effect a slow, gradual shifting of the first arm relative to the second arm in one direction of oscillation and a rapid shifting of the first arm relative to the second arm in the opposite direction of oscillation.

10. Traverse mechanism for group package forming apparatus comprising thread guiding means, a rock shaft connected to said means to reciprocate the latter to effect winding of a package, a first arm fast on the rock shaft, a second arm loose on the rock shaft, means for effecting oscillations of the second arm of uniform amplitude, and means connecting the second arm to the first arm for transmitting the oscillations of the second arm to the first arm and for causing a slow, gradual shifting of the first arm relative to the second arm in one direction of oscillation and a rapid shifting of the first arm relative to the second arm in the opposite direction of oscillation.

11. Traverse mechanism for group package forming apparatus comprising thread guiding means, a rock shaft connected to said means to reciprocate the latter to effect winding of a package, a drive shaft parallel to the rock shaft, and operating mechanism connecting the drive shaft to the rock shaft for effecting oscillation of the rock shaft to cause traverse movement of the thread guiding means and for additionally effecting a slow, gradual shifting movement of the rock shaft in one direction of oscillation and a rapid shifting movement of the rock shaft in the other direction of oscillation to effect gains of the traverse in opposite directions of the package, said operating mechanism including a pair of parallel arms oscillating about a common axis and operatively connected in series to transmit the aforementioned movements between the said shafts.

12. Traverse mechanism for group package forming apparatus comprising thread guiding means, a rock shaft connected to said means to reciprocate the latter to effect winding of a package, a drive shaft parallel to the rock shaft, and operating mechanism connecting the drive shaft to the rock shaft for effecting oscillation of the rock shaft to cause a traverse movement of the thread guiding means and for additionally effecting a slow, gradual shifting movement of the rock shaft in one direction of oscillation and a rapid shifting movement of the rock shaft in the other direction of oscillation to effect gains of the traverse in opposite directions of the package, said operating mechanism including a pair of parallel arms oscillating about a common axis, a separate cam for actuating each arm with the cams being carried respectively on the drive shaft and on one of the arms, and means for differentially driving said cams from the drive shaft.

JOSEPH P. McHUGH.
